UNITED STATES PATENT OFFICE.

DAVID W. PYE, OF BROOKLYN, NEW YORK.

METHOD FOR LAYING CAR FLOORS AND AISLE STRIPS.

Application filed December 31, 1927. Serial No. 243,889.

This invention relates to a method for laying car floors and it consists in the novel steps and procedure hereinafter described and claimed.

5 In carrying out the improved method a flooring composition of plastic material which contains ingredients that work together when mixed with a liquid binder causing a chemical setting-up action is used as a foundation. This foundation layer possesses sufficient flexibility as to effectually withstand the strains to which it is subjected in passenger car service.

10 A prime object of the present invention is to provide an economical and efficacious method for inserting blocks of tile in the said foundation layer to add to the appearance of the floor surface without subtracting from the resiliency or strength of the floor.

15 20 The tile is furnished in sheets with paper glued upon the polished surfaces of the blocks and these tile are cut from the sheet in the form of a group leaving the paper attached to the tile. The tile are tamped into the foundation layer with the paper side up. In order to assist in maintaining a regular and uniform positioning of the tile, a perforated template of sheet steel, beaver board, or any other stiff material that will not 25 buckle is provided. The perforations in the template correspond with the design in which the blocks are arranged. The template is laid upon the foundation layer just before it hardens and the tile inserted 30 through the perforations in the template and tamped flush with the surface of the foundation layer.

35 The tile is tamped into the foundation layer of plastic material just as the said material is beginning to harden so that the material which comes in contact with the faces of the tile blocks is additionally compressed or compacted and thereby made strong and firm at the walls of the mortises so formed in the material and which hold the tile blocks.

40 45 When the blocks have become set in the foundation layer, the template is removed and the upper surface of the foundation is gone over with a mason's flat trowel to smooth down any unevenness which might occur. The strips of paper which are permitted to remain adhering to the upper surfaces of the tile blocks will become discolored by the material removed by the trowel from 50 the body of the plastic material during the 55 smoothing operation. At the same time, the

said strips protect the upper polished surfaces of the blocks and prevent the trowel and the discoloring material from coming in contact with the said polished surfaces of the blocks.

60 After the plastic material of the floor hardens a cloth which has been dampened with water is wiped around the tile blocks. This wiping action softens and removes the 65 paper strips from the tile blocks leaving them clean and unmarred.

In the accompanying drawing:—

70 Figure 1 is a fragmentary horizontal sectional view of the end portion of a sleeping car showing lavatory floors and an aisle strip laid in pursuance of the new method;

Figure 2 is a plan view of a template used in carrying out the method;

75 Figure 3 is a plan view of tile blocks mounted upon a sheet of paper and used in carrying out the method;

Figure 4 is a fragmentary sectional view of the floor showing the position of the parts and materials before the tile blocks have been 80 tamped into the foundation layer;

Figure 5 is a similar view showing the tile blocks tamped into the foundation layer;

85 Figure 6 is a similar view showing the position of the parts when the floor has been completed.

90 As illustrated in Figure 1 of the drawing a sleeping car 1 is shown as being provided with an aisle strip 2 and lavatories 3 having floors 4, the said aisle strip and floors having 90 been laid in accord with the method described hereinafter.

95 In carrying out the method, a foundation layer 5 of plastic material is spread upon the floor of the car in soft condition. A template 6 having perforations 7 is laid upon the upper surface of the foundation layer 5. A sheet of paper 8 having tile blocks 9 glued thereon is used for holding the said tile blocks in flat condition. Several of the tile 100 blocks 9 with the paper 8 adhering to their upper or polished surfaces are cut from the said sheet and these tile blocks are inserted in the perforations 7 of the template 6. The blocks 9 are inserted in the said perforations 105 just as the foundation layer 5 begins to harden. A tamping tool 10 is applied to the strips of paper 8 at the upper surfaces of the blocks 9 which have been inserted in the perforations of the template and pressure in a 110 downward direction is applied to the said tamping tool whereby the blocks 9 are forced

down into the material of the foundation layer 5, and with the upper surfaces of the blocks flush with the upper surface of the said foundation layer. As the blocks are thus forced into the foundation layer they form recesses or pockets therein and compact or compress the material of the foundation layer about the walls of the said pockets so that the structure is solidified and strengthened around the blocks.

The tamping tool 10 is provided with a shoulder 11 spaced from the tile block engaging end of the tool a distance equal to the transverse thickness of the template so that when the said tool is used for embedding the blocks in the foundation layer the shoulder of the tool impinges the template and thus the upper surfaces of the blocks will be flush with the upper surface of the foundation layer.

After all of the tiles have been tamped into place, the template 6 is removed from the floor surface. A mason using a flat trowel (not shown) then goes over the upper surface of the foundation layer and smooths the said surface. In doing so some of the material of the foundation layer is scraped or moved upon the upper surfaces of the paper strips 8, thereby discoloring the said strips. Inasmuch as the strips are applied to the upper polished surfaces of the tile blocks they protect the said blocks and prevent the same from being scratched by the trowel or discolored by the material which is removed from the foundation layer during the said smoothing operation.

When the foundation layer has hardened and when the blocks 9 have become securely embedded therein, a damp cloth (not shown) is wiped over the strips 8 whereby the said strips are softened and are removed from the upper polished surfaces of the tile blocks, leaving the same polished and clean and positioned in the foundation layer in accordance with the arrangement of the perforations in the template. Thus a smooth floor or aisle strip is provided and the same is ornamented by the blocks which are different in color from that of the foundation strip and the presence of the blocks do not subtract from the strength of the floor or aisle strip and at the same time materially add to the ornamentation and attractive appearance thereof.

Having described the invention what is claimed is:—

1. The method of laying a floor consisting in spreading a layer of plastic material in soft condition to form a foundation, placing upon said foundation layer a perforated template, inserting in the perforations blocks of dimensions corresponding with the dimensions of the perforations of the tem-

plate, applying pressure to the blocks to embed them in the material of the foundation layer to a predetermined depth, and finally removing the template. 65

2. The method of laying a floor consisting in spreading a layer of plastic material in soft condition to form a foundation, placing upon said foundation layer a perforated template, inserting in the perforations blocks of dimensions corresponding with the dimensions of the perforations of the template, applying pressure to the blocks to embed them in the material of the foundation layer to a predetermined depth with the upper surfaces of the blocks flush with the upper surface of the foundation layer, and finally removing the template. 70 75 80

3. The method of laying a floor consisting in spreading a layer of plastic material in soft condition to form a foundation, placing upon said foundation layer a perforated template, inserting in the perforations blocks of dimensions corresponding with the dimensions of the perforations of the template, said blocks having a protecting sheet applied to certain of their surfaces, applying pressure to the blocks to embed them in the material of the foundation layer to a predetermined depth, removing the template, and finally removing the protecting sheet from the blocks. 85 90 95

4. The method of laying a floor consisting in spreading a layer of plastic material in soft condition to form a foundation, placing upon said foundation layer a perforated template, inserting in the perforations blocks of dimensions corresponding with the dimensions of the perforations of the template, said blocks having a protecting sheet applied to their upper surfaces, applying pressure to the blocks to embed them in the material of the foundation layer to a predetermined depth, removing the template, and finally removing the protecting sheet from the blocks by washing. 100 105 110

5. The method of laying a floor consisting in spreading a layer of plastic material in soft condition to form a foundation, placing upon said foundation layer a perforated template, inserting in the perforations blocks of dimensions corresponding with the dimensions of the perforations of the template, said blocks having a protecting strip applied to certain of their surfaces, applying pressure to the blocks to embed them in the material of the foundation layer to a predetermined depth, removing the template, smoothing the upper surface of the foundation layer, and finally removing the protecting strip from the blocks. 115 120

In testimony whereof I affix my signature.

DAVID W. PYE.
